[57] CLAIM

The ornamental design for a deskside data processing system, as shown and described.

DESCRIPTION

FIG. 1 is a top, front, right side isometric view of a deskside data processing system, showing our new design;

FIG. 2 is a front elevational view thereof;

FIG. 3 is a right side elevational view thereof;

FIG. 4 is a top plan view thereof;

FIG. 5 is a left side elevational view thereof; and,

FIG. 6 is a rear elevational view thereof.

The bottom of the deskside data processing system is unornamented.
